US00D754228S

(12) **United States Design Patent**
O'Neill et al.

(10) **Patent No.:** **US D754,228 S**
(45) **Date of Patent:** **** Apr. 19, 2016**

(54) **OPTICAL COMPONENT**

(71) Applicant: **olloclip, LLC**, Huntington Beach, CA (US)
(72) Inventors: **Patrick D. O'Neill**, Huntington Beach, CA (US); **Chong Pak**, Lakewood, CA (US)

(73) Assignee: **olloclip, LLC**, Huntington Beach, CA (US)

(**) Term: **14 Years**

(21) Appl. No.: **29/482,575**

(22) Filed: **Feb. 19, 2014**

(51) LOC (10) Cl. **16-06**

(52) U.S. Cl.

USPC **D16/130**

(58) **Field of Classification Search**

USPC D10/178; D14/240, 251, 358, 432, 433; D16/130, 134, 136, 154, 208, 219; 92/161; 359/544, 808, 811, 818, 819, 359/823, 824, 826, 827, 828; 362/365; 396/529; 455/90.3, 567, 569.1, 575.1, 455/575.8

CPC G02B 7/02; G02B 13/00; G02B 13/001; G02B 15/00

(57) **CLAIM**

The ornamental design for an optical component, as shown and described.

DESCRIPTION

FIG. 1 is a front, top, and right side perspective view of an optical component;

FIG. 2 is a back, bottom, and left side perspective view thereof;

FIG. 3 is a right side elevation view thereof;

FIG. 4 is a left side elevation view thereof;

FIG. 5 is a front side elevation view thereof;

FIG. 6 is a back side elevation view thereof;

FIG. 7 is a top plan view thereof; and,

FIG. 8 is a bottom plan view thereof.

The features illustrated in broken line depict portions of the optical component that form no part of the claimed design.

1 Claim, 8 Drawing Sheets
